(57) CLAIM

The ornamental design for a cotton slipper, as shown and described.

DESCRIPTION

FIG. 1 is a front view of a cotton slipper, showing my new design;

FIG. 2 is a rear view thereof;

FIG. 3 is a right side view thereof;

FIG. 4 is a top perspective view thereof;

FIG. 5 is a left side view thereof;

FIG. 6 is a bottom view thereof;

FIG. 7 is a top view thereof;

FIG. 8 is a top view of the cotton slipper of FIGS. 1–9, with the bamboo portion removed from the body of the slipper for clarity of disclosure; and,

FIG. 9 is a bottom perspective view thereof.

The broken lines in the drawings illustrate the portions of the cotton slipper, which form no part of the claimed design.
